BUILDER MOTION

John J. Sippel, Upper Darby, Pa., assignor to H. W. Butterworth & Sons Company, Philadelphia, Pa., a corporation of Pennsylvania

Application June 24, 1943, Serial No. 492,141

4 Claims. (Cl. 242—43)

This invention relates to builder motions for spinning machines and more particularly to builders motions for producing tapered packages.

An important object of the invention is the provision of an extremely simple and durable control mechanism for varying the length of the stroke and tapering the package, which mechanism is of such character that it may be readily utilized in multiple in spinning machines having a great number of spindles.

A further and more specific object of the invention is the provision of an apparatus of this character wherein a reciprocable member has imparted thereto a uniform motion and wherein means are provided for modifying this motion as to its effective length comprising a single movable part operatively engaging a lever carried by the reciprocable member and continuously shifting during the building period to vary the throw of the lever with relation to that of the reciprocable member thereby varying the length of the stroke.

Another object of the invention is to provide a construction of this character in which the length of the stroke at the beginning of the building motion may be very readily regulated, thus insuring the production of uniform packages.

These and other objects I attain by the construction shown in the accompanying drawings wherein, for the purpose of illustration, I have shown a preferred embodiment of my invention and wherein:

Figure 1 is a fragmentary transverse sectional view through a spinning machine embodying a builder motion constructed in accordance with my invention;

Figure 2 is a side elevation thereof;

Figure 3 is a section on line 3—3 of Figure 2;

Figure 4 is a section on line 4—4 of Figure 3;

Figure 5 is a section on line 5—5 of Figure 2; and

Figure 6 is a semi-diagrammatic view illustrating the drive employed.

Referring now more particularly to the drawings, numeral 10 generally designates a machine frame on which is suitably supported a builder drive generally designated at 11. The drive 11 comprise a casing having arranged therein a transversely reciprocable bar 12 and a transversely extending rotatable shaft 13 which is connected to the bar to reciprocate the same by a suitable cam and roller connection generally designated at 14. The reciprocable drive of bar 12 may be of any suitable type which will impart a uniform reciprocation to the bar and that here-

in shown, while preferred, is purely illustrative. Shaft 13 is at present illustrated as being driven by a longitudinally extending shaft 15 extending through the casing and driven from the motor 16. 5 Mounted upon the bar 12 for oscillation upon an axis transverse to the bar is a bell crank lever 17, one arm of which projects through a slot 18 in the upper wall of the casing and is provided with a fork 19 engaging a block 20 carried by a transverse link 21 forming the lower end of a parallel motion mechanism comprising a center oscillatory link 22 and side links 23. Side links 23 are secured to rock-shafts 24 at opposite sides of the machine, such rock-shafts bearing arms 25 10 through which a thread guide bar 26 is transversely oscillated to shift thread guides 27 with relation to the packages P which are being formed. The packages P are mounted upon opposite ends of transverse shafts 28, one of which 15 is herein shown, these shafts being driven as at 29 by a longitudinal shaft 30 which may be driven from any suitable source.

Extending through the wall of the casing as at 31 adjacent the bar 12 is a stub shaft 32, the inner 25 end of which bears a guide 33 in which is engaged a roller 34 carried by the second arm 35 of bell crank 17. The outer end of this stub shaft has a crank arm 36, the free end of which is forked and engages a block 37 mounted on a nut 38 30 which engages a vertically extending worm 39 forming the upper end of a shaft mounted for rotation in suitable bearings 40 supported by the casing of the unit 11. This shaft may be reversely rotated from a longitudinally extending shaft 41, 35 common to all units of the machine. Upon the vertically extending shaft is splined a clutch unit 42 through which either of gears 43 or 44 may be connected to the vertically extending shaft. The clutch element which engages the upper gear 40 is a positive clutch element as indicated at 45 whereas gear 44 is connected through a friction type clutch as at 46.

These clutches may be selectively engaged 45 through operation of a hand controlled shaft 47 likewise extending longitudinally of the machine and common to all units. This shaft through gearing 48 rotates a vertical worm 49 to elevate or lower a cage 50. Pivoted as at 51 upon bracket 52 is a lever 53 having at one end a fork 50 engaging the clutch unit 42 and at its opposite end an eye 54 surrounding worm 49 and engaged at its upper and lower faces by springs 55 extending between the eye and the ends of the cage. The spring mounting will permit variation in relieving movements imparted to the arms of

various units so that complete engagement of the clutches of such units may be properly effected even though a variation in movements is essential, as for example, when the positive clutch fails to properly engage initially or when through variation in wear of the friction clutches any variation in movement is necessary. Longitudinally extending shaft 41 is driven from motor 16 and drives gear 44 at a relatively high speed as through stub shafts 56. The gears 43 are driven at low speed by means of a take-off drive from shaft 41 indicated at 57 and including a reduction gearing generally designated at 58. Rotation of screw 39 is limited and accordingly movement of the arm 36 is limited under influence of the friction drive through engagement of the arm 36 with an adjustable stop 59 which may be carried by the same brackets 60 mounting the bearings for the screw 39. It will be understood that when the arm 36 comes into engagement with this stop the rotation of the screw will be checked through slipping at the friction clutch 46, this operation constituting the reset mechanism establishing the longest stroke of the builder motion.

In operation of the machine it may be assumed that the parts are in the solid line position of Figure 3 and that the building motion of packages P has just started. At this time, the positive clutch 45 will be engaged and screw 39 will rotate at a very slow speed thereby shifting arm 36 downwardly and rocking shaft 32 and guide 33. It will be noted from Figure 3 that at the beginning of this builder motion the inclination of the guide will, through its engagement with bell crank 17, cause this bell crank to shift with reciprocation of bar 12 to provide an accentuated motion of transverse link 21 and accordingly of thread guide bar 26. When the arm 36 has reached an intermediate position, such as that indicated at B, Figure 5, the groove of guide 33 will parallel bar 12 and accordingly the link 21 will be given a motion equal to that of the bar. As the oscillation of the guide continues beyond this central portion, the motion imparted to the bell crank will be the reverse of that imparted to the bar with the result that the stroke will be steadily shortened until the minimum stroke position indicated at C, Figure 3, is reached. At this time, the packages may be doffed and the position of the mechanism restricted to again begin the building motion.

It will be obvious that the above mechanism comprises an extremely simple and readily regulated means for controlling the building of tapered packages. It will be also obvious that the construction illustrated is capable of considerable modification without departing from the spirit of my invention.

I claim:

1. In a builder motion, a reciprocable member, means to impart a substantially uniform reciprocation to said member, a bell crank lever mounted on the member and having one arm thereof extending in the general direction of reciprocation of the member and the other arm projecting outwardly therefrom, a thread guide driven by the last-named arm, an inclined guide

with which the first-named arm is operatively engaged whereby the lever is oscillated in timed relation to the reciprocation of the member, means to vary the inclination of the guide, comprising a crank connected to said inclined guide, a rotatable worm operatively engaged with the crank, and means to rotate said worm in opposite directions, the means to rotate the worm in one direction including a friction clutch.

2. In a builder motion, a reciprocable member, means to impart a substantially uniform reciprocation to said member, a bell crank lever mounted on the member and having one arm thereof extending in the general direction of reciprocation of the member and the other arm projecting outwardly therefrom, a thread guide driven by the last-named arm, an inclined guide with which the first-named arm is operatively engaged whereby the lever is oscillated in timed relation to the reciprocation of the member, means to continually vary the inclination of the guide from a position where the oscillation of the bell crank causes said other arm to move in a direction supplementing the reciprocation of said member to a position where the movements of the said other arm and member are opposed, comprising a crank connected to said inclined guide, a rotatable worm operatively engaged with the crank, and means to rotate said worm in opposite directions, the means to rotate the worm in one direction including a friction clutch.

3. In a builder motion, a reciprocable member, means to reciprocate said member, a transverse arm mounted on the member for oscillation about a pivot transverse to the member, a thread guide driven by the arm, means operated by reciprocation of the member for oscillating said arm including an inclined guide operatively engaged with the arm, means constantly varying the inclination of said guide to thereby vary the extent of oscillation of the arm and the extent of movement of the thread guide, comprising a crank connected to said inclined guide, a rotatable worm, a nut on said worm with which said crank is engaged, and means to rotate said worm in opposite directions, the means to rotate the worm in one direction including a friction clutch.

4. In a builder motion, a reciprocable member, means to impart a substantially uniform reciprocation to said member, a bell crank lever mounted on the member and having one arm thereof extending in the general direction of reciprocation of the member and the other arm projecting outwardly therefrom, a thread guide driven by the last-named arm, an inclined guide with which the first-named arm is operatively engaged whereby the lever is oscillated in timed relation to the reciprocation of the member, said inclined guide being oscillatable about an axis arranged in the general plane of travel of the bell crank pivot, means to slowly oscillate the inclined guide about its pivot in one direction, means to rapidly oscillate the guide in the opposite direction including a friction clutch and a positive stop limiting oscillation of the guide in the last named direction.

JOHN J. SIPPEL.
